(57) **CLAIM**

The ornamental design for a projector equipped with a camera, as shown and described.

DESCRIPTION

FIG. 1 is a perspective view of front, top and right side of a projector equipped with a camera showing our new design; FIG. 2 is a perspective view of rear, top and left side thereof; FIG. 3 is a front view thereof; FIG. 4 is a rear view thereof; FIG. 5 is a left side view thereof; FIG. 6 is a right side view thereof; FIG. 7 is a top view thereof; and, FIG. 8 is a bottom view thereof.

The broken lines shown in FIG. 8 represent portions of the projector equipped with camera that form no part of the claimed design.
